UNITED STATES PATENT OFFICE

171,625

FOLDING PICNIC TABLE

Paul L. Wahl, Middletown, Conn.

Application May 20, 1953, Serial No. 25,127

Term of patent 14 years

(Cl. D33—14)

To all whom it may concern:

Be it known that I, Paul L. Wahl, have invented a new, original, and ornamental Design for a Folding Picnic Table, of which the following is a specification, reference being had to the accompanying drawing forming a part hereof.

Fig. 1 is a top plan view of a folding picnic table showing my new design;

Fig. 2 is a side elevational view thereof; and

Fig. 3 is an end elevational view of the folding picnic table.

I claim:

The ornamental design for a folding picnic table, as shown.

PAUL L. WAHL.
